DOOR LATCH

By Orenstein, 520 E. 21st St., Brooklyn, N.Y.

Filed June 14, 1962, Ser. No. 70,554

Term of patent 14 years

(Cl. D50—5)

FIG-3

FIG. 1 is a front elevational view of a door latch showing my new design;

FIG. 2 is a side elevational view; and

FIG. 3 is a top plan view.

I claim:

The ornamental design for a door latch, substantially as shown.
